UNITED STATES PATENT OFFICE

SAMUEL SPAGNOLA, OF TUCKAHOE, NEW YORK

ELECTRIC RECTIFYING APPARATUS

Application filed July 23, 1928. Serial No. 294,751.

This invention relates to a rectifying or transforming apparatus whereby high tension alternating current may be transformed into direct current, the object of the invention being to avoid certain objections or difficulties heretofore existing in rectifying apparatus now in use.

In carrying the invention into effect the alternating current is transformed by being passed through a rectifying transformer by which it is divided so that it may be passed through a plurality of insulators to electrodes arranged in a vacuum chamber. Within the said vacuum chamber are a plurality of nozzles having minute discharge openings, each of these nozzles being connected with a pipe manifold communicating with a pump by which mercury is forced through the said manifold pipes to the said nozzles in such a manner as to cause atomized sprays of mercury to bombard and electrically connect spaced apart electrodes arranged in said chamber by striking an arc between them this result in this case being effected by a mercury vapor or atomized spray, resulting in a copious liberation of electrons from a hot body. One electrode is electrically connected with a positive terminal of the rectifying load and the negative terminal is derived from the neutral point of the rectifying transformer which may be utilized for driving any direct current motor, certain radio, or other direct current apparatus. The condensed mercury spray in the vacuum chamber is returned to a well in the bottom of said chamber and from this well it flows downward to a tank or well from which it is taken by the mercury pump to be again forced upward into the vacuum chamber.

To avoid the use of a special vacuum pump for the vacuum chamber, an exhaust apparatus is preferably connected with the mercury pump in such a manner that a column of mercury forced upward under pressure may be returned by gravity so as to pass through a restricted orifice and thereby create a suction through a pipe connected with the said vacuum chamber, and thus, by the induced suction, maintain the proper degree of vacuum in the said vacuum chamber, this suc-

tion apparatus working on the general principle of the well known Sprengel pump.

In the accompanying drawings, Fig. 1 is a somewhat diagrammatic view illustrating the invention. Fig. 2 is a detail view of the exhaust device for the vacuum chamber.

Referring to the drawings, the alternating current passes through conductors 12 to a rectifier transformer consisting of primary and secondary elements 13 and 14. From this rectifying transformer the current passes through a plurality of conductors 15 and insulators 16 to a plurality of electrodes 17 arranged in a vacuum chamber afforded by a casing 18 and cover 19. The apparatus includes an electric motor 20 which is operatively connected with a mercury pump 21 by which mercury is forced through a pipe 22 connected by manifold pipes 23 with nozzles 24 having minute discharge openings, said nozzles being herein shown as arranged between the cathode electrode or electrodes 25 in the said vacuum chamber and the said electrodes 17. By virtue of this arrangement of the parts above referred to atomized sprays of mercury issuing from the said nozzles will electrically connect the said cathode and electrodes by striking an arc between the same.

It will be noticed that the anodes 17 are solid bodies against which the atomized mercury sprays impinge, in contradistinction to mercury or other liquid anodes.

Owing to the atomization of the mercury greater contact areas are afforded for the current, thereby increasing the capacity output of the rectifier due to the increased ionization of the molecules of the gas and resulting in an increase of electron flow to the anode of the rectifier. The atomized spray mercury condenses and runs down the sloping bottom 18^a of the vacuum chamber, afforded by the casing 18, to a central well 26 which receives the condensed mercury and returns the same through a pipe 27 to a supply receptacle or well 28 communicating, through a suction feed pipe 29, with the mercury pump 21.

The discharge or delivery pipe 21^a connected with the mercury pump 21 communicates not only with the feed pipe 22 but is branched so as to connect with a pipe 30 the

upward extension of which discharges mercury into a suction chamber afforded by a casing 31 so that the mercury discharged into the said chamber and passing downward through a restricted orifice 32 will induce a suction through a pipe 33 communicating with the vacuum chamber within the casing 18 and will therefore serve to maintain a proper vacuum within the said chamber.

10 This suction device operates on the principle of the well-known Sprengel pump, as will be understood.

In starting the apparatus the mercury feed pipe 22 may be closed by a valve 34, and when a proper vacuum has been effected within the vacuum chamber of the casing 18 the said valve 34 may be opened for the purpose of spraying the mercury between the electrodes 25 and 17, thereby avoiding the use of a special exhaust pump for the said vacuum chamber. Thus as soon as a proper vacuum is obtained in the vacuum chamber, the rectifier is energized, and the valve 34 is opened; and thus the transformer or rectifier is set into operation without the assistance of a special starter, as is required in mercury rectifiers now generally in use.

To prevent crossing currents between the different sets of electrodes, as also to prevent short circuiting, due to mercury spray which may accidentally reach the casing 18, barriers 37 are preferably interposed between the sets of electrodes and also between the electrodes and such casing.

35 From the foregoing it will be understood that the invention presents certain advantages over mercury rectifiers or transformers now in use in that by electrically connecting a plurality of sets of electrodes by a plurality of atomized sprays of mercury so much surface conducting areas are presented that more current may be rectified by an apparatus of a given size than is possible by the mercury rectifiers now in use.

40 As another advantage of the invention it may be mentioned that in the use of this improved rectifying apparatus, no preheating of the anodes is necessary, as the mercury spray or vapor becomes incandescent and thus imparts sufficient heat to the anodes to enable them to function properly. Also the invention eliminates the necessity of an auxiliary maintaining electrode, as also the necessity of a special exhaust pump for the vacuum chamber, or a special starter for the apparatus.

45 By so directing the mercury or confining the streams of atomized mercury spray in the direction of the anodes, a greater number of positive or ionized bodies are produced, thus increasing the electron stream to the anodes, and thereby eliminating random velocities at the crater of the mercury pool of the cathode. Also sputtering and bombardment of these mercury molecules causes the liberation

of ions and electrons produced by friction, and also carries down and precipitates the foreign gases so that the rectifier is completely freed from such gases.

It will be understood that the invention is not necessarily limited to the details of construction herein shown, as it is believed to be broadly new to connect a plurality of sets of electrodes, in a rectifier vacuum chamber, by means of a plurality of atomized mercury sprays.

Having thus described my invention, I claim and desire to secure by Letters Patent:

1. An electric rectifying apparatus comprising a vacuum chamber, a plurality of sets of spaced-apart electrodes therein and comprising anodes made of solid material, and means for electrically connecting said electrodes by a plurality of atomized mercury sprays projected from the cathodes against the anodes. 80

2. An electric rectifying apparatus comprising a vacuum chamber, a plurality of sets of spaced-apart electrodes therein, a mercury receptacle, a mercury force pump communicating with said receptacle, a plurality of spray nozzles through which the mercury is forced from the cathodes to the anodes to form a plurality of atomized mercury sprays, pipe connections between said pump and said nozzles, and means for driving said pump. 90

3. An electric rectifying apparatus comprising a casing affording a vacuum chamber, a plurality of sets of electrodes in said chamber, a mercury receptacle, a plurality of spray nozzles in said chamber, means for forcing mercury through said nozzles to form a plurality of atomized mercury sprays between said electrodes, barriers between the sets of electrodes and also between the sets of electrodes and said casing to prevent cross currents, and means for returning the condensed mercury to said receptacle. 100

4. An electric rectifying apparatus comprising a vacuum chamber, spaced-apart electrodes therein, a mercury receptacle, a mercury pump communicating with said receptacle, spray nozzles in said chamber, pipe connections between said pump and said nozzles, means for driving said pump, and suction means, operated by mercury forced upward by said pump, for exhausting air from said vacuum chamber. 110

In testimony whereof I affix my signature.

SAMUEL SPAGNOLA. 120
